LOW-WATER ALARM.

1,127,010.

Specification of Letters Patent.

Patented Feb. 2, 1915.

Application filed July 25, 1914. Serial No. 353,242.

To all whom it may concern:

Be it known that we, BYERS W. KADEL, JOHN A. PILCHER, and HARRY W. CODDINGTON, citizens of the United States, residing 5 at Roanoke, in the county of Roanoke and State of Virginia, have invented certain new and useful Improvements in Low-Water Alarms, of which the following is a specification.

10 This invention relates to low water alarms for boilers and its object is to overcome the defects of such devices as now known and used. It is especially adapted for use with locomotive boilers and may be employed to 15 control the supply of the feed water to a boiler, as well as to provide a warning to the attendants that the water is dangerously low.

With these objects in view the invention 20 consists in the construction and combination of parts as will be herein set forth and particularly claimed.

In the drawing which forms a part of these specifications, Figure 1 is a side elevation of a locomotive having our invention applied thereto and Fig. 2 is a similar view of the invention detached from the locomotive and drawn to an enlarged scale over that of Fig. 1.

25 Referring to the drawings where like parts are given the same reference numbers wherever they occur, 1 represents the locomotive having a boiler 2. The boiler has the customary fire-box 3, wagon-top sheet 4, 30 crown sheet 5 and fire-box end sheets 6 and 7.

At 8 we insert into the boiler through the wagon-top sheet 4, a steam fitting 9. The lower or internal portion 9^a of this steam 40 fitting 9, is tubular in form, the tube 9^a being open at its lower end at 10. At 11 the steam fitting 9 is provided with an externally threaded portion adapted to be screwed into a threaded opening in the 45 wagon-top sheet of the boiler.

The upper or external portion of the steam fitting 9 is made in the form of a cross-T, having four outlets. To the outlet 12 an expansion element or pipe 13 is attached, this expansion pipe being disposed 50 at a slight inclination above the horizontal as it proceeds away from the outlet 12 for drainage and is preferably composed of a metal such as copper or brass having a relatively high coefficient of expansion.

The outlet 12 of the cross-T to which the expansion element is attached is adjacent the junction of the lower or tubular portion 9^a of the steam fitting 9 to the cross-T portion of the same. The outlet 14 is diametrically opposite and in an axial line with the expansion element 13 while the outlet 15 is in an axial line with the depending or tubular portion 9^a of the steam fitting 9.

The steam fitting 9 thus forms a fluid connection between the boiler and expansion pipe, its fluid communication being made with the boiler at a point below the normal water level therein and immediately over the highest point of the crown sheet.

The expansion element 13 terminates in a hollow fitting 16, the expansion element being in open fluid communication with the hollow fitting. The said hollow fitting 16 is provided with a clean-out opening 17 and a blow-off connection 18 from the cavity thereof, and an external trunnion 19, which latter forms a pintle for the upper end of a lever 20.

The lever 20 is pivoted at 21 to a bracket 22 which bracket is shown as mounted on the boiler by means of the studs 23. The lower end of the lever 20 is provided with an adjusting screw 24 having a check nut 25, and the point of this adjusting screw is 20 adapted under certain conditions to contact the stem 26 of an air or steam valve 27. This valve 27 may be of any convenient construction that will open when the screw 24 is pressed against the stem 26 and close 25 when the screw 24 is released.

The operation of our invention is as follows: The open lower end of the tubular portion 9^a of the steam fitting 9 is disposed at a height above the crown sheet of the 35 boiler corresponding with what may be considered a dangerously low position of the water line. As long as the water is above this point and the end 10 of the tube 9^a is submerged, the pressure of the steam will 40 keep the steam fitting 9 and the expansion element 13 filled with water, and inasmuch as this water will have little circulation its 45 temperature will fall somewhat below that of the steam and water within the boiler. 50 With the parts so filled with water the screw 24 should be adjusted to not quite contact the stem 26 of the valve 27 so that the valve 27 will be closed against the passage 55 of steam or air from the supply pipe 28 to 60

the adjusting screw 29. In addition to this, the slight clearance between the point of the adjusting screw and the stem 26 of the valve 27 will prevent the vibrations of the parts of the mechanism from effecting the valve 27 when the locomotive is moving. If the water level in the boiler now falls so as to expose the open end 30 of the tube 9^a the water contained in the steam fitting 9 and in the expansion element 13 will fall into the boiler and these parts will fill up with steam which will be at a higher temperature than the water previously in these parts. Consequently the pipe 13 will expand and the lever 23, pivoted at 21, will push the point of the adjusting screw up against the stem of the valve 27 and its further movement will open this valve, admitting air or steam to the whistle 29. This alarm will be nearly the harbinger of the state of the water in the boiler and the injectors will be turned out. As soon as the water level rises and again submerges the open end of the tube 9^a the steam will be shut off from the alarm fitting 9 and the expansion element 13. The steam imprisoned in these parts will gradually condense and its space will be filled with water drawn up from the boiler and as this water slightly chills the expansion pipe will contract, shutting off the valve and withdrawing the point of the adjusting screw from its contact with the stem of the valve 27, the mechanism now being in condition for another alarm as caused by the water level fall.

Now if we provide a guide for the fitting 10, this guide being secured to the bracket 20 by means of the bolts 31.

Among the faults of existing devices of this character is the difficulty of freeing the various parts from scale and other matter from the boiler. To overcome this we have provided clean-out openings 14 and 15 in the cross-T portion of the steam fitting 9^a and a clean-out opening 17 in the end of the boiler fitting 16, all of these openings being ordinarily provided with pipe plugs as shown equivalent. When, however, it is desired to clean out the parts these plugs are removed and all the main passages are open so that they may be readily cleaned. The clean-out opening 17, like the opening 15, is in an axial line with the pipe 13 so that this pipe may be washed and scraped, the previously described location of the clean-out opening 15 serving likewise for the tube 9^a.

A further difficulty encountered in the present forms of low water alarms is the difficulty with which they may be tested.

Now for us we are aware it has been necessary heretofore to lower the level of the water in the boiler in order to test the operative condition of the mechanisms. This has been an undesirable feature in that it

carries with it more or less danger from the possibility of exposing the crown sheet. For example, when lowering the water to test the alarm the only way of knowing when the danger point is reached is by the alarm itself. And if this should be inoperative it will be seen that there is danger of blowing off too much water with consequent burning or blowing down of the crown sheet. To overcome this difficulty we provide the blow-off connection 18 with a pipe line leading therefrom to any suitable point of discharge and we supply in this line a blow-off valve 32. This blow-off connection must be located beyond or near the extremity of the expansion element in order that the water influencing the expansion or contraction of the same may be blown off. The expansion element will thus form a thoroughfare between the steam fitting 9 and the blow-off line, and consequently all of the chilled water in the expansion element may be forcibly expelled and displaced with hot water from the boiler when the valve 32 is open. With the device equipped with this blow-off line the operative condition of the mechanism may be tested at any time by opening the valve 32 for a few seconds which will allow the chilled water to be expelled from the expansion element, upon which it will immediately fill up with hot water from the boiler. This will set off the alarm if it is operative, and the matter of testing becomes so simple that it may be done at frequent intervals.

Another fault of the present forms of low water alarms as applied to locomotive boilers is that they connect to the back head or to the side of the boiler. When the locomotive rocks laterally or assumes the varying gradients of the track longitudinally the undulations of the water may either advance or retard the action of the alarm.

In the present invention the depending tube 9^a is located immediately over the high point of the crown sheet so that the device at all times responds to the levels of the water that obtain at this, the critical point, and the undulations of the water will have no undesirable effect.

We are aware that various similar devices are now known which use the expansion of a tube to open an alarm valve, and we also know that some of these are alternately expanded and contracted by steam and water as in our device. Hence we do not claim the broad idea of such as our invention.

What we do claim, however, is:

1. In a low water alarm, the combination with a boiler of a cross T having four outlets, said outlets being arranged in pairs disposed in axial lines, an expansion element in fluid communication with the said cross T and attached thereto at one of the said outlets, a fluid connection between the said

boiler and the said cross T and being attached thereto at one of the said outlets adjacent the point of attachment of the said expansion element, the remaining two of the said outlets being provided with closures and being adapted to form clean-out openings in axial lines with the said expansion element and the said fluid connection respectively, and an alarm adapted to be operated by the expansion of the said expansion element.

2. In a low water alarm, a boiler, a thermostatically actuated expansion element in fluid connection therewith, an alarm adapted to be actuated by the said expansion element, and a blow-off line from said expansion element whereby the chilled fluid contained therein may be replaced with heated fluid and the operative condition of the mechanism be thereby determined.

3. In a low water alarm the combination with a boiler of an expansion tube having fluid connection therewith at its inner end, said expansion tube terminating at its outer end in a hollow fitting, the cavity thereof being in open communication with and being disposed in an axial line with the cavity of the said expansion tube, the said hollow

fitting being provided at its outer end with a clean-out opening and on its side with a blow-off connection, said clean-out opening and said blow-off connection being in fluid communication with the cavity of the said hollow fitting.

4. In a low water alarm, a boiler, a thermostatically actuated expansion element, a fluid connection between the said boiler and the said expansion element, an alarm adapted to be actuated by the said expansion element, and a blow-off line in fluid communication with the said expansion element, the said fluid connection and the said blow-off line being so connected to the expansion element that the cavity of the said expansion element will form a fluid thoroughfare between the said fluid connection and the said blow-off line.
